UNITED STATES PATENT OFFICE.

ALPHEUS ARTER, OF LISBON, OHIO.

HARNESS ATTACHMENT.

SPECIFICATION forming part of Letters Patent No. 777,325, dated December 13, 1904.

Application filed June 3, 1904. Serial No. 211,000. (No model.)

To all whom it may concern:

Be it known that I, ALPHEUS ARTER, a citizen of the United States, residing at Lisbon, in the county of Columbiana and State of Ohio, have invented new and useful Improvements in Harness Attachments, of which the following is a specification.

This invention relates to harness attachments, and more particularly to spreaders or guides for the reins or lines of double harness. In devices of this class as constructed heretofore supporting frames or holders with separable members inclosing roller or antifrictional means have been employed. The operation of these devices has been more or less tedious in applying a line or spreader-strap thereto and in pursuing the disassociation of said parts.

The primary object of the invention is to provide an exceedingly strong, durable, and yet simple and economical line guide or spreader to which the rein or line can be easily and quickly applied without requiring a separation of the parts or removing or unbuckling the supporting or hanger strap or connection.

A further object of the invention is to provide a guide having such construction that the line or spreader-strap may be readily inserted therein or separated therefrom without requiring such line or strap to be unbuckled.

The invention primarily consists of a frame or supporting means of a practically rigid character having antifrictional devices supported thereby and separated by a space sufficiently wide to permit the insertion and withdrawal therebetween of a rein or line when the latter is disposed edgewise without requiring movement or adjustment of said antifrictional devices from their normal position.

The invention further consists in the details of construction and arrangement of the several parts, which will be more fully hereinafter set forth.

In the drawings, Figure 1 is a perspective view of a guide embodying the features of the invention. Fig. 2 is a front elevation of the guide, showing the manner of inserting and withdrawing the rein or line in dotted lines and said rein or line in normal position in full-line section. Fig. 3 is a longitudinal section

taken centrally through the guide. Fig. 4 is a front elevation of the guide-frame, showing the antifrictional devices removed.

Similar numerals of reference are employed to indicate corresponding parts in the several views.

The numeral 1 designates a guide-frame having a head 2 with a slot 3 therein for the attachment of a hanger-strap, chain, or other analogous device. Depending from the opposite portions of the head is a pair of legs 4, each of which has an inwardly-projecting bearing-stud 5, extending only partially across the space between the legs, so that an opening will be formed between the inner terminals of the said studs. Antifrictional devices, in the present instance in the form of rollers, are held on the bearing-studs 5 and are of such width as to provide a space or throat 7 between them. Between the rollers 6 and the head 2 an unobstructed opening 8 is formed for the reception of the rein or line, and communicating with the said opening is a central slot or recess 9, formed in said head for the purpose of permitting the rein or line to be disposed edgewise in a vertical direction in withdrawing or applying the same with respect to the guide.

The rollers 6 are applied to the studs 5 when the legs 4 are initially bent outwardly; but after the legs have been struck in or disposed in parallelism the rollers are maintained in constant spaced relation and efficiently operate as antifrictional means to obviate wear on the line, rein, or strap engaging the same during longitudinal movement through the guide.

When the rein, line, or strap is inserted in the guide, it is arranged edgewise in a vertical direction and pushed between the inner opposing faces of the rollers, the upper edge being caused to enter the slot or recess 9 to permit the lower edge to be cleared from the rollers. From this position the line, rein, or strap is turned until it becomes horizontally disposed. In withdrawing the line or rein it is again arranged in edgewise relation to the space or throat between the rollers and pressed downwardly between the latter.

From the foregoing it will be seen that a rein, line, or strap may be quickly applied to

or withdrawn from the guide without requiring a separation of the parts of the latter, and, further, the cost of manufacture or production of the guide is reduced to a minimum in view of the absence of movable members or pivoted parts. It will also be understood that changes in the proportions and dimensions may be resorted to at will.

Having thus fully described the invention, 10 what is claimed as new is—

1. A guide for the purpose set forth, having transversely-extending antifrictional devices with a throat between the inner opposing faces thereof.
- 15 2. A guide for the purpose set forth, having a rigid frame carrying transversely-extending antifrictional devices spaced apart to form an entrance and exit throat for the frame.
- 20 3. A guide, having a rigid frame terminally carrying transversely-extending antifrictional devices spaced apart from each other to form an entrance and exit throat for the frame.
- 25 4. A guide having a rigid supporting means and a pair of antifrictional devices held at one extremity of said means, the inner opposing faces of said antifrictional devices being spaced apart from each other to form a throat.
- 30 5. A guide for the purpose set forth having a rigid supporting means, and transversely-aligned antifrictional devices with an intervening space between their inner opposing faces.
- 35 6. A guide for the purpose set forth having a supporting means, and terminal transversely-extending rollers spaced apart to form a throat extending longitudinally of the guide.
- 40 7. A guide for the purpose set forth having a supporting means, and transversely-extending antifrictional devices having their inner ends spaced apart from each other to form a passage centrally disposed with relation to the supporting means.
- 45 8. A guide for the purpose set forth having a supporting means with a clearance-recess at

one extremity, and antifrictional devices arranged at the opposite extremity and provided with a throat between their inner opposing faces in alignment with said recess.

9. A guide for the purpose set forth, having a rigid frame with a recessed head at one extremity, and antifrictional devices held in the opposite extremity of the frame and spaced apart from each other to form a throat in line with said recess, the frame having an opening therethrough between the head and the 55 antifrictional devices.

10. A guide for the purpose set forth having a supporting means, and rollers forming the closure for one end of the supporting means and provided with a throat between the inner opposing surfaces thereof.

11. A guide for the purpose set forth having a rigid frame with legs, and transversely-extending antifrictional devices held by the terminals of said legs and spaced apart to form 65 an entrance and exit throat at one end of the guide.

12. In a guide for the purpose set forth, a rigid frame having a head at one end formed with a clearance-recess and also provided with 70 legs, and antifrictional devices held by the terminals of said legs, the inner opposing faces of said antifrictional devices being spaced apart from each other to form a throat.

13. In a guide for the purpose set forth, a rigid frame having legs with inwardly-projecting terminal studs, and transversely-extending antifrictional devices held on the said studs, the inner opposing faces of said antifrictional devices being spaced apart from 80 each other to form a throat.

In testimony whereof I have hereunto set my hand in presence of two subscribing witnesses.

ALPHEUS ARTER.
